J. G. DALY

FILE CLEANING TOOL

Filed Feb. 24, 1925

FIG. 6

Inventor

JOHN G. DALY

By C. B. Birkenbeul

Attorney

UNITED STATES PATENT OFFICE.

JOHN G. DALY, OF PORTLAND, OREGON.

FILE-CLEANING TOOL.

Application filed February 24, 1925. Serial No. 11,226.

To all whom it may concern:

Be it hereby known that I, JOHN G. DALY, a citizen of the United States, and a resident of Portland, in the county of Multnomah and State of Oregon, have invented a new and useful File-Cleaning Tool, of which the following is a specification.

This invention relates generally to files such as are used by metal workers and other artisans, and particularly to means for cleaning files which have become filled with grease, dirt, soft metals, etc.

The first object of this invention is to provide an exceedingly simple and efficient tool for cleaning files.

The second object is to eliminate the waste usually occurring when a file is discarded on account of being dirty instead of being actually dull.

The third object is to provide an inexpensive and highly efficient form of advertising novelty.

The fourth object is to conserve time on the part of mechanics by enabling them to use a clean file, which must necessarily cut faster than a file filled with foreign matter.

These results are attained in the manner set forth in the following specification as illustrated in the accompanying drawing, in which:

Figure 1 is a front elevation of the device of which Figure 2 is a plan and Figure 3 is a side elevation. Figure 4 is a vertical section taken along the line 4-4 in Figure 1. Figure 5 is an enlarged longitudinal section through a portion of a file and the file-engaging portion of the device. Figure 6 is a vertical section taken along the line 6-6 in Figure 5.

Similar numbers of reference refer to the same parts throughout the several views.

Referring in detail to the drawing, the device consists of a somewhat heart-shaped member 10 having relatively straight edges 11 and 12 and a V notch 13 formed therein. The portions 14 and 15 of the edges are preferably rounded. A groove 16 is completely formed around the edge of the device and terminates in a pair of holes 17 in the notch 13. The member 10 is preferably made of wood or papier-mâché, and in some cases is

provided with a printing surface on its flat side for the purpose of bearing advertising.

The edges 18 are preferably chamfered, as indicated. Around the groove 16 is securely placed a round wire 19, preferably of a soft metal such as solder, whose ends 20 are forced into the holes 17.

In Figures 5 and 6 are illustrated a portion of a file 21 whose teeth 22 are shown being cleansed of the foreign matter 23.

The operation of the device is as follows: It is held in one hand and moved along the cutting edges of the file under a slight pressure, as indicated in Figures 5 and 6. The teeth 22 quickly cutting their way into the soft metal wire form a counterpart of themselves in the wire which scrapes out any foreign matter which may be lodged there, completely cleaning the teeth.

If desired a straight-sided wire 19 (not shown) can be employed which will more effectively scrape out the foreign matter, the round one having been shown merely on account of the fact that round wire is more readily obtained than is one of a special cross section.

I am aware that file cards and similar devices have long been employed for the purpose of cleaning files, I therefore do not claim such devices broadly but I do intend to cover all such forms and modifications of this device as fall fairly within the appended claims.

I claim:

1. The combination of a holder having flat sides and a groove formed around the edge thereof; and a soft wire partially embedded in said groove.

2. The combination of a holder having relatively straight lateral and lower edges and having a V-shaped recess in its upper edge and having a groove formed in the edges thereof terminating in holes in said V-shaped recess; and a soft wire partially embedded in said groove surrounding said holder and having its ends secured in said holes, a portion of said wire projecting beyond said holder throughout its entire length except that portion thereof which is within said holes.

JOHN G. DALY.
